Des. 238,837

Patented Feb. 17, 1976

238,837

STACKABLE CHAIR

George C. Mulhauser, 545 Clinton Road,
Paramus, N.J. 07652

Filed Aug. 7, 1973, Ser. No. 386,322

Claims priority, application Sweden Feb. 7, 1973

Term of patent 14 years

U.S. Cl. D6—65 Int. Cl. D6—01

FIG. 1.

FIG. 2.

FIG. 3.FIG. 4.FIG. 5.FIG. 1 is a three-quarter front perspective view of a stackable chair showing my new design;

FIG. 2 is a three-quarter back perspective view of a stackable chair showing my new design;

FIG. 3 is a front elevational view of the stackable chair of FIG. 1 and FIG. 2 showing my new design;

FIG. 4 is a rear elevational view of the stackable chair of FIG. 1 and FIG. 2 showing my new design;

FIG. 5 is a bottom view of the stackable chair of FIG. 1 and FIG. 2 showing my new design.

It should be understood that the hidden side of the stackable chair shown in FIG. 1 is identical to the side shown fully in FIG. 1.

I claim:

The ornamental design for a stackable chair, as shown and described.
